SPANNER WRENCH WITH DEPTH GAUGE

Leon J. Rozankowski, Baltimore, Md., assignor to Western Electric Company, Incorporated, New York, N. Y., a corporation of New York

Application February 25, 1953, Serial No. 338,655

3 Claims. (Cl. 81—90)

This invention relates to assembling tools, and more particularly to wrenches for advancing threaded, cylindrical members into engagement with each other in a predetermined relationship.

In the manufacture of communication cables, it is frequently convenient to produce a cable in sections and to finish the ends of each section with a connector so that any desired number of sections may be quickly fastened together to form cables of various lengths, as demands may require.

The design and construction of these connectors frequently involve the assembling of a threaded bushing into threaded engagement with a housing, where the bushing must assume a definite and predetermined position with respect to the housing so that the connector on the end of one length of cable will interlock with a similar connector on the end of another length of cable chosen at random. In the mass production of cable connectors composed of bushing-housing assemblies which are positioned in a predetermined axial and angular relationship, it has been difficult heretofore to manufacture great numbers of these assemblies with reasonable uniformity and with assurance that a finished connector will interfit with another, even though reasonable tolerances are allowed.

An object of the invention is to provide new and improved assembling tools.

Another object of the invention is to provide new and improved wrenches having means for gaging the distance of axial advance of a bushing into threaded engagement with a housing.

Another object of the invention is to provide new and improved wrenches having means for controlling the angular relationship between a bushing and a housing.

An apparatus embodying certain features of the invention may comprise an assembling tool for positioning an element of an assembly in a predetermined relation with respect to an apertured element of such assembly. This tool may comprise means for engaging the first-mentioned element to advance it into the aperture in the apertured element, and means for gaging the relationship between the thus assembled elements.

A complete understanding of the invention may be obtained from the following detailed description of a device constituting a specific embodiment thereof, when read in conjunction with the appended drawing, in which:

Fig. 1 is a top plan view of a wrench embodying the invention shown in conjunction with articles to be assembled therewith;

Fig. 2 is a right side elevation showing the wrench, a bushing, and a housing in operative position, with parts broken away for purpose of illustration;

Fig. 3 is a front elevation of the elements shown in Fig. 1 with parts broken away to show the configuration of the wrench handle, and

Fig. 4 is a section taken along line 4—4 of Fig. 2.

Referring now in detail to the drawing, and more particularly to Fig. 2, there is shown a wrench body 10 having upwardly extending ears 11 and 12. The ears 11 and 12 are provided with aligned bores 13 and 14, respectively, for receiving a pin 15. A handle 16 having a transverse bore 17 therethrough is pivotally mounted between the ears 11 and 12 by means of the pin 15 passing through the bores 13, 14 and 17. As shown in Fig. 3, the angle through which the handle 16 may pivot is limited. Pivoted movement of the handle 16 is controlled on the right by the abutment of the handle 16

with a surface 18 of the wrench body 10, and on the left by the abutment of the handle 16 with the inclined portion 20 of the wrench body 10. A lug 21, having a ground surface 19, is formed integral with the handle 16.

The wrench body 10 is provided with downwardly depending arcuate lugs 22 and 23. These lugs are spaced apart and interfit with similar lugs 24 and 25 projecting outwardly from a threaded bushing 26 designed for threaded engagement with an internally threaded housing 27 (Fig. 2). Upon rotation of the handle 16 in a clockwise direction, as seen in Fig. 1, the lugs 22 and 23 of the wrench engage and turn the lugs 24 and 25 of the bushing 26, thereby advancing the bushing axially and inwardly with respect to the housing 27.

The wrench body 10 is provided with gaging surfaces 30 and 31, each of which lies in a different horizontal plane, as seen in Fig. 2. The housing 27 is provided with arcuate lugs 32 and 33, which are spaced apart and have coplanar upper surfaces 34 and 35, respectively.

Operation

With the lugs 22 and 23 of the wrench in engagement with the lugs 24 and 25 of the threaded bushing 26, as shown in Fig. 2, the handle 16 is rotated in a clockwise direction to advance the bushing into the housing 27. Rotation is continued until the plane developed by the gage surface 31, indicated in Fig. 1 by the term "under," assumes a position coplanar with or slightly below the plane developed by the surfaces 34 and 35 of the housing, and the plane developed by the gage surface 30 is coplanar with, or slightly above, the plane developed by the surfaces 34 and 35 of the housing. With the bushing and the housing in this axial relationship, the handle 16 is canted, as shown in Fig. 3. Upon further rotation of the handle 16 in a clockwise direction, the stop lug 21 on the handle contacts the lug 32 of the housing 27, thereby causing the bushing 26 to assume a predetermined angular relationship with respect to the housing.

It is thus apparent that the gage surfaces 30 and 31 of the wrench provide a means for determining when the bushing has been advanced a predetermined distance into the housing, while the vertical disposition of the planes developed by these surfaces represent the maximum and minimum variations tolerable from the predetermined distance. Obviously, the stop lug 21 is the means for locating the bushing in the desired angular relationship with respect to the housing after the bushing has been advanced a predetermined distance into the housing.

While the particular embodiment of the invention described hereinabove is utilized in connection with a bushing and housing assembly in threaded engagement, it is obvious that the scope and utility of the invention extends to telescoping structures of the type described whether or not the elements thereof are in threaded engagement. Also, the member inserted into the housing by use of a tool embodying the invention may be a generally solid cylinder rather than an annular or tubular member.

What is claimed is:

1. An assembling wrench for advancing a bushing having outwardly projecting, arcuate lugs into threaded engagement with a threaded, shouldered housing and for positioning said bushing and housing in a predetermined axial and angular relation, which comprises a disk-like body member having a portion of the upper surface thereof lying within a plane which is parallel to and disposed a predetermined distance from another plane developed by another portion of said upper surface, depending arcuate lugs on the body member for engaging the lugs on said bushing, upwardly projecting ears on the body member, a rod pivotally mounted between said ears for rotating the body member to advance the bushing into the housing until one of said parallel surfaces lies within the outermost point on said housing and the other parallel surface lies beyond the outermost point on said housing thereby positioning the bushing axially with respect to the housing, and a lug projecting downwardly from said rod for engaging the shoulder on the housing when the rod is pivoted and rotated to posi-

3

the bushing angularly in a predetermined relation with respect to said housing.

2. An assembling wrench for engaging a generally cylindrical bushing having a notched periphery at one end thereof and for inserting the bushing into a predetermined position within an aperture in a housing, which comprises a disk having a notched skirt designed to engage the notched periphery of the bushing and to advance the bushing axially into the aperture when the wrench is rotated, a gage mounted on said disk for indicating the depth to which the bushing has been advanced into the aperture, and a lever mounted pivotally upon the disk to facilitate rotation of the wrench and to engage the housing when the lever is pivoted and rotated to position the bushing in a predetermined angular and axial relationship with respect to the housing.

3. An assembling wrench for engaging a generally cylindrical bushing having a notched periphery at one end thereof and for inserting the bushing into a predetermined position within an aperture in a housing, which comprises a disk having a notched skirt designed to engage the notched periphery of the bushing and to advance the bushing axially into the aperture when the

wrench is rotated, a gage mounted on said disk for indicating the depth to which the bushing has been advanced into the aperture, said gage being marked to indicate the maximum and the minimum limits of depth tolerated, and a lever mounted pivotally upon the disk to facilitate rotation of the wrench, said lever having a lug designed to engage the housing when the lever has pivoted and has been rotated to advance the bushing to a depth between said limits, thereby positioning the bushing in a predetermined angular and axial relationship with respect to the housing.
